UNITED STATES PATENT OFFICE

ARNOLD J. MICHAEL, OF PLYMOUTH, VERMONT

INTERNAL COMBUSTION ENGINE

Application filed January 13, 1930. Serial No. 420,579.

This invention relates to an internal combustion engine of the four cycle double acting type.

A drawback to this type of engine has been that a rather great length of cylinder has been required.

An object of this invention is to produce an engine of the double acting type that shall not be excessive in length.

10. A further object is to construct such a compact engine in a manner that shall not sacrifice any accessibility of the parts of the engine.

Other objects of my present invention will 15. be apparent to those skilled in the art from the following description and appended claims.

In the drawings accompanying the description,

20. Fig. 1 is a transverse vertical section of one form of engine embodying my invention.

Fig. 2 is a longitudinal vertical view partly in section of two adjacent units of the engine.

25. Fig. 3 is a section taken along line 3-3 of Fig. 1 and showing two adjacent units.

Fig. 4 is a perspective view of the dual piston cylinder.

30. Fig. 5 is a perspective view of the compression head.

The water-jacket engine block 1 is provided with a combustion chamber 2 at its upper end and another combustion chamber 3 at one side thereof. Block 1 is bored to form the cylinders 4. Cylinder 4 receives the piston member 5 which in turn is bored to receive the compression head 6, which is fastened to the cylinder 4 as will be described later.

The top of the engine is removable, in the manner well understood in internal combustion engines, giving free access to the interior of the engine.

45. In assembling the engine it is contemplated

that the member 5 together with its connecting rod 17, but without its head 11, will be first inserted in the cylinder 4. The compression head 6 is then inserted from above into the interior of member 5 and is bolted to the cylinder 4. The head 11 is then screwed into place.

Member 5 comprises a cylindrical member 7 which is bored somewhat off center to provide a comparatively thick wall at 8. A channel 9 is located in this wall 8 starting slightly above the groove 9' and terminating at the port 10 communicating with the interior of the member 5. Member 7 is tapped at the upper end thereof to receive the threaded head 11. Member 7 is provided with grooves 12 at its upper end and head 11 with groove 13. Each of the grooves 9', 12 and 13 is adapted to receive the usual piston ring. The member 5 is formed with ears 14 at its lower end provided with the apertures 15 to receive the wrist pin 16 which is furnished with a bushing. This wrist pin carries the connecting rod 17 which transmits the power to the crank shaft 18.

The member 6 comprises a head portion 19 and the two side arms 20. The head 19 is provided with grooves 21 to receive piston rings. The arms 20 are tapped at their lower ends at 22 to receive bolts 23 which secure member 6 to the cylinder 4. Spacer segments 230, 230' are used to properly space the member 6 from the walls of cylinder 4 so as to allow the sides of member 5 to reciprocate in the space so formed. It will be seen that there is sufficient space between the arms 20 to allow the free movement of wrist pin 16 and connecting rod 17.

Combustion chamber 2 forms the upper part of cylinder 4 and is provided with intake and exhaust valves 26 and 27 operated by the cam shaft 24. A spark plug 28 is located in chamber 2.

Combustion chamber 3 adjacent one side of cylinder 4 communicates with groove 9 and

the interior of member 5 by port 29. At the upper end of the stroke of piston 5 the bottom of groove 9 is in alignment with port 29 while at the lower end of the travel of the piston the port 10 is in alignment with port 29. Chamber 3 is provided with intake and exhaust valves 30 and 31 operated from cam shaft 32. Chamber 3 is also provided with a spark plug 33 which is carried by a metal plug 25 which screws into an opening 25'. This opening is of sufficient size so that, when the plug 25 is removed the interior of chamber 3 is easily accessible and valves 30 and 31 can be easily removed.

15 The operation of the device is as follows:

In Fig. 1 it may be assumed that chamber 2 contains a charge of gas under compression and is at the upper end of its stroke. Member 5 contains a charge of gas ready to be compressed. The gas in chamber 2 is ignited by 28 whereupon the charge is exploded forcing the piston 5 downwardly. During this down stroke the gas in member 5 and combustion chamber 3 is being compressed since both 25 valves 30 and 31 are closed as is well understood. At the bottom of the stroke ports 10 and 29 are in alignment and the compressed gas is readily exploded by ignition from plug 33. At this point exhaust valve 27 opens 30 and when, as a result of the explosion in chamber 3, the member 5 is forced upwardly the burned gases in cylinder 4 will be forced out past the valve 27. Due either to the usual flywheel or to power strokes of the other cylinders in the engine, the piston 5 is now drawn down. Exhaust valve 27 having closed and intake valve 26 having opened, a fresh charge of gas will be drawn into the cylinder 4. At the same time, the exhaust 35 valve 31 having opened, the burned gases in member 5 will be forced out past the valve 31. It will be seen that due to the external channel 9 and the port 10, the interior of member 5 always communicates freely with chamber 45 3. Thus there is no undue resistance to the expulsion of burned gases or to the admission of a fresh charge of gas. On the subsequent upward stroke the intake valve 26 closes, and thus the charge in cylinder 4 is compressed. 50 At the same time, exhaust valve 31 having closed and intake valve 30 having opened, a fresh charge of gas will be drawn into cylinder 5. Thus during the four strokes or cycles of the piston two power strokes occur. 55 The under side of both cylinders 4 and 5 being open to the crank case, in those engines which utilize the splash system of lubricating the cylinder walls, cylinder 4 will be lubricated on the upstroke while cylinder 5 will be lubricated on the down stroke by the splash from crank case 2.

It will be seen that, due to the fact that the interior wall of member 5 is only perforated at its upper end by the small port 10, it is necessary to provide rings only at the

upper end of member 6. This fact enables the connecting rod 17 and wrist pin 16 to travel to within a short distance of the upper end of member 6. This structure enables the engine to be very compact. Moreover this compactness is obtained with no sacrifice of simplicity or accessibility of ports.

70 Various modifications, of course, may be made, within the scope of the invention as defined in the appended claims. My invention may be applied to the V and radial types of engines as well as to engines with the cylinders in line.

Having described my invention, I claim:

1. In an internal combustion engine of the 80 double acting type, the combination of a cylinder, a combined cylinder and piston member adapted to reciprocate in said cylinder and comprising a cylindrical member closed at one end, a longitudinal channel in the outer wall of said cylindrical member terminating in a port opening into the interior of said cylindrical member, an intake and exhaust port in the wall of said first-mentioned cylinder in alignment with said channel and 85 said first-mentioned port and a stationary compression head within said combined cylinder and piston member.

2. In an internal combustion engine of the 90 double acting type, the combination of a cylinder, a combined cylinder and piston member adapted to reciprocate in said cylinder and comprising a cylindrical member having a removable head at one end thereof, a longitudinal channel in the outer wall of 95 said cylindrical member terminating in a port opening into the interior of said cylindrical member, an intake and exhaust port in the wall of said first-mentioned cylinder in alignment with said channel and said first-mentioned port and a stationary compression head within 100 said combined cylinder and piston member.

3. In an internal combustion engine of the 110 double acting type, the combination of a cylinder, a combined cylinder and piston member adapted to reciprocate in said cylinder and comprising a cylindrical member closed at one end, and adapted to be connected to a connecting rod at the other end, a port in the side wall of said cylindrical member adjacent the closed end thereof and a longitudinal channel in the outer side of said wall extending from said port, an intake and exhaust port in the wall of said first-mentioned cylinder in alignment with said channel and 115 said first-mentioned port and a stationary compression head within said combined cylinder and piston member.

4. In an internal combustion engine of the 125 double acting type, a cylinder having a combustion chamber at one end thereof, a second combustion chamber adjacent one side thereof and communicating with said cylinder by a port in the side wall of said cylinder, a 130

combination piston and cylinder member comprising a cylinder closed at one end, a longitudinal channel in the outer wall of said member terminating in a port opening into the interior of said member, said channel and port being aligned with the port communicating with the second combustion chamber so that the interior of said member is always in communication with said second combustion chamber.

5 The foregoing specification signed at Ludlow, Vermont, this twenty-eighth day of December, 1929.
